UNITED STATES PATENT OFFICE.

ABRAHAM RITTER, OF NEW YORK, N. Y.

CLASP.

SPECIFICATION forming part of Letters Patent No. 668,390, dated February 19, 1901.

Application filed August 22, 1900. serial No. 27,644. (No model.)

To all whom it may concern:

Be it known that I, ABRAHAM RITTER, a citizen of the United States, residing in the borough of Manhattan, in the city and State of New York, (whose post-office address is No. 5 East Ninety-seventh street, in said borough,) have invented certain new and useful Improvements in Clasps, of which the following is a specification.

10 My invention relates to improvements in clasps for suspending chatelaine-bags or other articles.

The object of my invention is to provide a hook from which various articles may be suspended and which when used as a support for chatelaine-bags is adapted to be firmly yet detachably secured to a body belt or band worn around the waist.

It is common to suspend various toilet articles, such as chatelaine-bags, vinaigrettes, watches, &c., by means of a hook from a waist-belt. Such hook usually consists of a simple plate of metal bent into an inverted-U shape, and has at the end of one of its legs 25 a loop from which the various articles are suspended. The weight of the suspended articles and tightness of the belt are supposed to keep the hook in place. In practice, however, the motions of the body tend to work the hook 30 out of the belt and it is often lost, with its attachments. My improved clasp is constructed with a fastener which prevents this accident without unsightly protuberance.

It is usual to construct a chatelaine-bag hook of thin flexible metal covered with leather and then bent. In preference to this I construct my clasp of two rigid metal plates, one of them having the inverted-U shape to 40 form a hook for attachment to the belt and the other constituting a separate front piece or shield, which may have any desired ornamental outline and is covered with leather, which may be decorated, if desired, or made to match the bag with which it is to be used. 45 The parts thus separately made—to wit, the hook and the front piece or leather-covered shield—are riveted or soldered together, and the front piece or shield not only acts as a cover for the front of the hook, but serves to 50 assist in stiffening and strengthening the hook.

My improvement further relates to a par-

ticular construction of clipping device by which the clasp is secured to the belt or readily detached therefrom, as hereinafter described.

In the accompanying drawings, Figure 1 is a front view of my improved clasp. Fig. 2 is a side view of the same. Fig. 3 is a vertical section on the line 3, Fig. 1. Fig. 4 is a horizontal section on the line 4, Fig. 2.

A represents the front plate or shield, which is made of a stiff plate of metal and is covered in front with a facing L, of leather, which may be turned back around the edges 65 of the plate and fastened with cement.

The belt-hook B is constructed in inverted-U form of stiff metal strengthened by a vertical rib r at back and fastened to the back of the plate by riveting or soldering and extending downward, as shown, for the attachment of the hook or loop C, which projects from the bottom of the clasp for the reception of any article to be carried, such as a bag D.

Mounted in bearings on the inner face of 75 the front leg of the hook B or on the inner face of the plate A is a horizontal rock-shaft E, on the central part of which is a projecting lug F, which may be made integrally with the shaft or separate and secured thereto. 80 One end of the shaft E is bent at right angles to form an operating-handle G, provided at its extremity with a knob g.

H represents a spring-clip riveted at its upper end on the inner side of the plate A or 85 hook B and at its lower end is bent in horizontal position, where it is formed with serrations or teeth h to engage the belt or band on which the hook may be placed, so as to securely hold it in position. The spring-clip H 90 retires by its resilience from the hook-plate B when the rock-shaft handle G and lug F are in the retracted position shown in dotted lines in Fig. 2, thus releasing the hook and permitting its removal from the belt. When 95 the handle F is thrown up into the position shown in full lines in Fig. 2, the projecting lug G carried thereby presses the spring-clip H into engagement with the belt or band, so as to securely clip the same and prevent the 100 escape of the hook or clasp therefrom. In this position the handle F of the rock-shaft rests in a nearly vertical position coincident with the front plate A, so as to avoid any pro-

jection therefrom, and the lug G on the shaft is so disposed that the pressure of the spring-clip H tends to hold the parts in the clasped position.

- 5 A transverse groove b is made in the face of the belt-hook, directly opposite the edge h of the clip H, to render its grip on the belt more secure. The spring-clip H being attached wholly to the front member of the clasp leaves 10 the rear leg of the belt-hook B without any protuberance or obstruction to interfere with inserting it in the belt.

15 My mode of making the front plate or shield A separately from the belt-hook B has many important practical advantages. The hook requires to be rigid enough to sustain the pressure of the spring-clip, and it would not be practicable to cover with leather a plate possessing the necessary rigidity and subsequently 20 bend it into the form of a hook without cracking or injuring the leather. By making the front piece or shield of a separate piece and covering it with leather I accomplish the double result of having the article 25 look like the ordinary hook and yet of stiffening the article and presenting a firm and strong support for the lever.

Having thus described my invention, the following is what I claim as new therein and 30 desire to secure by Letters Patent:

1. The combination of the front plate A, the hook-plate B secured thereto, the spring-clip H fastened by one end to the plate A and

having an inturned serrated free end, the horizontal rock-shaft E mounted in bearings 35 on the face of the plate A and having operating-handle F projecting from its extremity beyond the edge of the plate A and the projecting lug G fixed to the rock-shaft and operating in conjunction with the spring-clip to 40 force the same into locked position or permit its retirement as described.

2. The combination of the front plate A, the spring hook-plate B, made of a separate piece of metal secured to the front plate A, 45 the spring-clip H secured at one end to the inner face of the plate A, the rock-shaft E having a projecting handle F and a lug G projecting from the shaft at an angle to the handle F and operating to force the clip-plate H 50 into engagement with the hook-plate B as described.

3. In a chatelaine-bag clasp, the combination of a belt-hook, a covered face-plate made in a separate piece, attached to said hook, a 55 spring-clip attached to the front member of the hook and tending by resilience to retire from the rear leg of the hook, leaving the same free for insertion in the belt and a cam device carried by a rock-shaft mounted on the 60 face-plate to force the spring-clip into locking position, as described.

ABRAHAM RITTER.
